(57) **CLAIM**

The ornamental design for a personal computer, as shown and described.

DESCRIPTION

FIG. 1 is a perspective view of the front, top and right side of a personal computer showing our new design with a movable stand;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of front, top and right side thereof shown in an alternative position;

FIG. 9 is a perspective view of front, top and right side thereof shown in another alternative position;

FIG. 10 is a rear perspective view thereof without a movable stand; and,

FIG. 11 is a perspective view thereof showing usage.

The broken lines shown in FIG. 11 are for environmental purposes only and form no part of the claimed design.
